UNITED STATES PATENT OFFICE.

JOHN S. SEARS, OF NEW YORK, N. Y.

DESIGN FOR AN ARTICLE OF MANUFACTURE.

52,197.

Specification for Design.

Patented July 16, 1918.

Application filed September 29, 1917. Serial No. 194,094. Term of patent 7 years.

To all whom it may concern:

Be it known that I, JOHN S. SEARS, a citizen of the United States of America, and a resident of the borough of Manhattan, city, county, and State of New York, have invented a new, original, and ornamental Design for an Article of Manufacture, of which the following is a specification, reference being had to the accompanying drawing, showing a front view of a statuette embodying my design.

While I have shown my design as embodied by way of example in a statuette, I want it to be understood that the application of the design is not limited to statuettes,

as it may obviously be embodied in various other articles of manufacture, such as dolls, cut-out dinner cards, bean-bags, and paper-weights. It is to be understood that my claim includes all substantial equivalents of my design as shown and described.

Attention is called to applicant's companion application Serial No. 123,990 covering similar subject matter.

I claim:

The ornamental design for an article of manufacture substantially as shown and described.

JOHN S. SEARS.
